STRINGED MUSICAL INSTRUMENT

Filed Dec. 20, 1929

UNITED STATES PATENT OFFICE

CHARLES HABERMAN, OF NORTH BERGEN, NEW JERSEY, ASSIGNOR TO OSCAR SCHMIDT, INC., OF JERSEY CITY, NEW JERSEY, A CORPORATION OF NEW JERSEY

STRINGED MUSICAL INSTRUMENT

Application filed December 20, 1929. Serial No. 415,373.

The invention relates to stringed musical instruments and has more particular reference to the type known as "Hawaiian guitars", which are usually played with the use of picks on the fingers of the right hand, for the melody, and with a so-called "steel" held in the left hand, for the accompaniment.

It has been found in practice, more particularly in the case of beginners, that the arm manipulating the steel soon becomes tired or cramped, with the result that the pleasure of playing is interfered with, and, in the case of beginners, progress is substantially delayed. Because of this, means have heretofore been provided, as disclosed in Letters Patent No. 1,758,626 of May 13, 1930, for supporting the steel in a manner permitting of its manipulation in the playing of the guitar in substantially the same free way as when held by the player's hand, but without strain or effort on the part of the player in the holding of the same. Such means comprises a supporting rod mounted on the instrument in a position above and lengthwise of the strings, and a sliding universal joint connection between the steel and said rod whereby the steel may be freely manipulated for playing engagement with the strings. The supporting rod of this prior device was mounted on the instrument in different ways to permit of its movement transversely of the strings in the manipulation of the string-engaging member, but such ways were found to be somewhat expensive and also cumbersome; by the latter term meaning that the transverse movement of the rod in the manipulation of its supported string-engaging member was not as free as desirable. For such reason, it has been the object of the present invention to improve the steel supporting means of the aforesaid application in a way to render the same more effective by increasing the ease and freedom of operation of the steel, and also to simplify and cheapen the same. This object I attain by means of the present invention as hereinafter described and claimed and as illustrated in the accompanying drawings, in which—

Fig. 1 is a plan view of a guitar equipped with a playing attachment embodying the invention; the attachment being shown, by full and dotted lines, in two different positions.

Fig. 2 is a side view, also showing, by full and dotted lines, two different positions of the attachment.

Fig. 3 is an enlarged cross section on line 3—3 of Fig. 1.

Fig. 4 is a similar view showing the steel in a different playing position.

To explain in detail, the instrument shown is a so-called "Hawaiian guitar" of usual construction, the same comprising the body portion 2 equipped with strings 3 mounted thereon in usual manner.

Mounted on the body portion 2 is a supporting rod 4 which extends longitudinally of the strings in a position above the same where they overlie the frets 5; this rod, as here shown, being pivotally mounted on the body 2 by means of a short vertically ranging extension 6 at one end thereof loosely fitting in a socket 7 of said body, whereby the rod is permitted a swinging movement above the strings in a direction transversely thereof, as indicated in Fig. 1.

The steel hereinbefore referred to, indicated at 10, has a sliding connection with the rod 4 through the medium of a universal joint connection whereby it may be readily manipulated for playing engagement with the strings. The connection of the steel with the rod as here shown is the same as that disclosed in the aforesaid application. It comprises a sleeve 11 which is loosely mounted on the rod for longitudinal sliding and turning movements thereon. This sleeve carries a fixedly connected block 12 to which the steel is attached, by means to be presently described, for sliding and pivotal movements relatively thereto.

The steel 10 as here shown is cut away at its center to provide an opening 13 through which the supporting rod 4 extends, whereby the lower edge 10', constituting the steel proper, is in position beneath the rod for engagement with the strings, while the upper portion, constituting the handle, is in posi-

tion above the rod for convenient grasping by the player.

A threaded pin 14, attached to the steel in a position extending perpendicularly across its opening 13, passes loosely through an opening in the block 12 to effect a pivotal connection of the steel with said block. A coiled spring 15 surrounding said pin 14 and expanding between the block 12 and the top wall of the opening 13 in the steel, acts to normally hold the latter in a raised position spaced from the strings.

With the steel mounted on the rod 4 in the way shown and described, the player may grasp the upper part of the steel and readily shift the same for usual playing engagement with any one or more of the strings, that is, the steel may be shifted lengthwise of the strings by a sliding movement on the rod, as indicated by the full and dotted line positions of the same in Fig. 1; or it may be rocked or tilted on the rod to bring it to an angular position for so-called "tipping" of the strings, as shown in Fig. 4; or it may be moved transversely of the strings by a swinging movement of the rod to permit of its tipping different strings, also as shown in Fig. 4; or it may be moved bodily downward against the pressure of the spring 15 for simultaneously engaging all of the strings, as in "barring", as shown in Fig. 3; or it may be swung horizontally about its pivot 14 for barring the strings at different points in the length thereof, this horizontal turning of the steel also facilitating the manipulation of the same in that it readily adapts itself to the various angular positions assumed by the hand in shifting the steel to its different playing or string-engaging positions.

By reason of the supporting rod 4 being pivoted only at one end, it has a free swinging movement over the strings not permitted by the supporting rod of the aforesaid application and thereby permitting of a more ready and free manipulation of the supported steel. Furthermore, the rod 4 of the present device is of spring metal, permitting of its perpendicular movement relatively to the strings, as shown by the full and dotted line positions of Fig. 2. This is of importance in that it permits of the ready movement of the steel to and from a position of engagement with the strings somewhat independently of that permitted by its sliding connection with the block 12 against the pressure of the spring 15; in fact, when the steel is adjacent the free end of the rod 4, the perpendicular yield of the latter is sufficient to permit of the engagement of the steel with the strings without the necessity of any downward pressure of the steel against the spring 15. As the steel is moved along the rod towards the pivoted end of the latter, however, and the yield of the rod thereby decreases, the nec-

essary downward movement of the steel on the rod for engagement with the strings is of course permitted by greater yielding of the spring 15.

What I claim is:

1. In combination with a stringed musical instrument, a playing attachment comprising a supporting bar extending lengthwise of the strings and being pivotally mounted on the instrument for swinging transverse movement above the strings, and a string-engaging member slidably mounted on the swinging supporting bar for longitudinal and transverse movements relatively to the strings.

2. In combination with a stringed musical instrument, a playing attachment comprising a supporting bar extending lengthwise of the strings and being pivotally mounted at one end on the instrument for swinging transverse movement above the strings, and a string-engaging member slidably mounted on the swinging supporting bar for longitudinal and transverse movements relatively to the strings.

3. In combination with a stringed musical instrument, a playing attachment comprising a supporting bar extending lengthwise of the strings and being pivotally mounted at one end on the instrument for swinging transverse movement above the strings and also being movable at its free end toward and from the strings, and a string-engaging member slidably mounted on the supporting bar for longitudinal, transverse and perpendicular movements relatively to the strings.

4. In combination with a stringed musical instrument, a playing attachment comprising a supporting bar extending lengthwise of the strings and being pivotally mounted at one end on the instrument for swinging transverse movement above the strings and also being movable at its free end toward and from the strings, a string-engaging member slidably mounted on the supporting bar for longitudinal, transverse and perpendicular movements relatively to the strings, and means yieldingly connecting the string-engaging member with its supporting rod whereby it is capable of perpendicular movement relatively to the strings independent of that permitted by the rod.

5. In combination with a stringed musical instrument, a playing attachment comprising a supporting bar extending lengthwise of the strings and being pivotally mounted on the instrument for swinging transverse movement above the strings, and a string-engaging member slidably mounted on the swinging supporting bar for longitudinal and transverse movements relative to the strings, said member being in the form of a straight-edged bar of a length sufficient to engage the full set of strings in a direction transversely thereof.

6. In combination with a stringed musical instrument, a playing attachment comprising a supporting bar extending lengthwise of the strings and being pivotally mounted on the instrument for swinging transverse movement above the strings, a string-engaging member in the form of a straight-edged bar of a length sufficient to engage the full set of strings in a direction transversely thereof, and a universal joint connection between said member and the pivoted supporting bar whereby the member is capable of longitudinal, transverse and tilting movements relatively to the strings.

15 In testimony whereof I affix my signature.
CHARLES HABERMAN.
